Application May 17, 1957, Serial No. 46,220

Term of patent 14 years

(Cl. D45—4)

FIG. 1

FIG. 2

FIG. 3

FIG. 4

FIG. 5

Fig. 1 is a top plan view of an expandable link chain embodying my new design with the conventional appearing expandable links shown in dotted lines and in contracted position;

Fig. 2 is a side elevation of the expandable link chain shown in Fig. 1;

Fig. 3 is a view similar to Fig. 1 with the expandable links in an expanded position, portions of the conventional appearing bottom links being visible between the expanded top links;

Fig. 4 is an enlarged top plan view of one of the series of top links located adjacent to the expandable portion of the chain; and

Fig. 5 is an enlarged side elevation of two of the series of top links located adjacent to the expandable portion of the chain.

The characteristic features of my design reside in the portions shown in full lines in the drawing and comprise marginal depressed areas associated with centrally disposed raised ridges.

I claim:

The ornamental design for an expandable link chain for a bracelet or similar article, substantially as shown and described.
